UNITED STATES PATENT OFFICE

ALLAN S. BARROWS, OF LOS ANGELES, CALIFORNIA, ASSIGNOR TO THE YOUNGSTOWN STEEL DOOR CO., OF CLEVELAND, OHIO, A CORPORATION OF OHIO

DUMP CAR

Application filed April 23, 1928. Serial No. 272,039.

This invention relates to improvements in dump cars.

One of the serious difficulties encountered in the operation of railway dump cars is that of maintaining a tight or sealed joint around the edges of the dump doors. It is well known that railroads and shippers lose many thousands of dollars annually, due to leakage around the door edges, and it is a common experience to observe straw or the like, stuffed in the joints around the door edges to prevent leakage. Open joints around the doors are due primarily to either or both of two causes; one is the failure or impairment of the door operating or locking mechanism proper, with the result that the doors are not forced to or held in fully closed position; the other is on account of the bending, buckling, warping, or other distortion or deformation of the door around the edges. As is well known, dump doors are subject to severe service conditions, particularly from dropping of the lading onto the doors from a considerable height. The impact of the lading under these conditions tends to deform the door and cause gaps and openings around the edges. While it is possible, and in fact common, to provide means to compensate for wear or slack occurring in door operating mechanisms, it is obvious that no amount of adjustment or compensation therein will overcome actual deformation of the doors themselves which permit of openings or gaps being formed between the edges of the doors and the surrounding fixed parts of the car body.

One object of my invention, therefore, is to provide a dump door and associated car parts so constructed that sealed joints are not only obtained when the parts are first assembled, but which function, under subsequent tendency to deform from impact of lading, to automatically serve to maintain the sealed joints, whereby to prevent losses from leakage.

A specific object of my invention is to provide a sheet metal door so formed that any depression occurring in the central area or zone thereof, from impacts of lading, will automatically tend to force the edge portions

of the door upwardly or in a reverse direction to the induced depression or deformation when the door is properly supported by the usual hinges and suitable door operating mechanism, whereby an effective seal will be maintained around the door edges. 55

Other objects of the invention will more clearly appear from the description and claims hereinafter following.

In the drawings, forming a part of this specification, Figure 1 is a vertical, transverse, sectional view of a portion of a drop-bottom car, showing my improvements in connection therewith. Figure 2 is a top plan view of the floor door, detached, shown in Figure 1. Figure 3 is an enlarged sectional view of an improved slope sheet and corresponding to the line 3-3 of Figure 1. Figures 4 and 5 are views similar to Figure 1, illustrating two other embodiments of the invention. And Figure 6 is a similar view, broken away, and illustrating a still further modification with respect to the fixed elements of the car with which the door edge co-operates. 70

Referring first to the construction illustrated in Figures 1, 2, and 3, the drop-bottom car is shown provided with channel center sills 10-10, transversely extending beams or diaphragms 11-11, side wall 12, and side stakes 13. As will be understood, in a car of the type indicated, the diaphragms or needle beams 11 are spaced longitudinally of the car and generally a single floor door is employed between each pair of said needle beams in the portion of the car between the usual trucks. In the drawings, I have deemed it necessary to illustrate only one door, since this is sufficient for explanation of my improvements. The improved pivoted floor door is indicated generally by the reference character A and the same is shown as hingedly mounted at its inner edge at 14 to suitable hinge brackets 15 secured to the center sills. Preferably, the hinge members 16, generally two in number per door, are extended entirely across the door beyond the free edge thereof, the extensions being indicated at 17, whereby said members serve as braces for the door on the underside thereof, as will be understood. Any suitable 95

operating mechanism for the door may be employed, a conventional form being indicated and consisting of a flexible chain or other connector 18 attached at its free end to the extension 17, the chain or connector winding around an operating shaft 19.

As common in this type of car, the operating shaft 19 is shown disposed in the space above the diaphragms or needle beams and in side of the vertical stakes and beneath a side slope sheet 20, the latter extending lengthwise of the car and having its upper longitudinal flanged edge 21 riveted to the bottom portion of the sheet constituting the side wall 12. Said sheet 20 slopes downwardly and inwardly, having a main deflecting section 22 and a vertical flange 23 along its bottom edge, the latter terminating against the tops of the diaphragms or needle beams.

In cars of this general type, with an operating shaft located as shown, difficulty has been experienced heretofore in many instances, due to deformation of the slope sheet above the shaft. Such deformation frequently occurs from impact of lading, which may bend or distort the sheet to such an extent as to cause it to engage and bind against the shaft and flexible connections therearound. To overcome this difficulty, and without any appreciable increase in expense, I corrugate the slope sheet 20 intermediate its top and bottom edges, with corrugations 24-24, as shown in Figures 1 and 3, said corrugations extending in the direction of the slope of the sheet so as not to interfere with discharge of the lading therefrom when the doors are opened, while giving a very rugged and substantial formation to the slope sheet and minimizing tendency of the same to deflect, it being obvious that the corrugations act more or less as struts between the secured upper and lower longitudinal edges of the plate.

In the embodiment of my invention shown in Figures 1 and 2, the door A is flat for the major portion of its area. Around each of its edges, the door is preferably provided with a downwardly extending integral flange 25 for increasing strength, said flange being suitably cut away at those points where the hinge braces 16 and 17 necessarily pass therethrough. In addition, along the side and free edges of the door, the sheet metal thereof is formed with a comparatively shallow, upwardly extending arcuate rib 26, the same being disposed above the main plane of the door sheet. Said arcuate rib around the three sides mentioned, is adapted to co-operate with corresponding arcuate flange sections 27 on floor plates or strips 28, one of which is shown in Figure 1, and has its upwardly extending flange riveted to the lower flange 23 of the slope sheet. Along the side edges of the door it will be understood that the floor strips are secured to the corresponding cross

bearers or needle beams along the tops thereof. The inner or hinged edge of the door extends beneath a longitudinally extending combined floor and cover plate 29, as clearly shown in Figure 1. With the construction so far described, it will be observed that a tight, sealed joint is formed around the edges of the door when the latter is in its normal, closed position, best shown in Figure 1.

To maintain this sealed condition, the door A has incorporated therein, diagonally disposed ribs 30-30 which merge at the center of the door into a more or less rectangular formation, as indicated at 31. Said ribs 30 are also preferably of arcuate cross section and furthermore are of the greatest depth or height at the center of the door where they coalesce, as indicated at 31. Stated otherwise, the ribs 30 are offset upwardly or pressed upwardly from the main plane of the door sheet and gradually taper out or become shallower as they approach the corners of the door, and ultimately become merged with the normal plane of the door sheet, as indicated at 32.

With the door having the ribs 30-30, as above described, and the door properly supported at its hinged and free edges, any tendency of the central portions of the door to be bent or deflected downwardly will be neutralized or compensated for by the ribs which will tend to lengthen under the impact of the lading, and this, in turn, will result in a tendency of the edges of the door to be pressed or deflected upwardly, thus maintaining the sealed joints. Stated otherwise, my improved door is what may be termed arched in its central area or zone, and the distance between any two opposite edges along the surface of the door will be greater than the straight line distance between such two edges, and, consequently, as the sheet metal gives or yields at the center of the door under impact, this longer line or section tends to straighten out and, assuming that the door is adequately supported, such straightening out or elongation of the metal produces an upward forcing of the edge portions of the door and a retaining of the close contact between such edges and the fixed co-operating elements of the car.

Referring to the construction illustrated in Figure 4, the parts of the car body are the same as in the form of the invention shown in Figure 1, except for the sealing strip or plate 127, which is here shown as an angle bar riveted to the lower flange of the slope sheet 120. The door B of this construction is preferably provided with a reinforcing marginal flange 125, and within the area defined by said flange, the door sheet is curved upwardly in arcuate or arch form, as indicated at 130, the door sheet preferably having incorporated therein what approximately corresponds to a portion of a spherical

surface. In this construction, the combined hinge strap and door braces 116 are curved to conform to the door sheet, it being understood that in the illustration of Figure 4 the 5 section of the door is approximately at the center thereof, whereas the combined strap and door brace 116 is at some distance from the plane of the section, which accounts for the difference in the curves of the member 10 116 and of the sheet comprising the door B. It will be understood that deflection of the door B in any central area or zone will produce the same result as hereinbefore described for the door A.

15 Referring to the form of the invention illustrated in Figure 5, the car body parts are the same as in the other described figures, except that the slope sheet 220 has secured to its lower flange a specially formed strip 227. 20 The latter has a vertically extending flange 228 directly riveted to the bottom flange of the slope sheet. The strip 227 then has an outward, horizontally extending section 229, and then a downwardly and outwardly sloping 25 flange 230.

The door C in this embodiment is provided with a downwardly extending flange 225 along its hinged edge and side edges, and at its free edge said flange is inclined outwardly, as indicated at 50, so as to snugly fit against the flange 230 of the floor strip 227 and form a tight seal therewith.

In the door C, the arching effect is obtained by a panel 330 offset upwardly from 35 the general main plane of the door sheet, said panel 330 merging with the flat portions 51 of the door sheet by means of downwardly inclined walls 52—52.

40 In Figure 6, the construction of the door C is the same as shown in Figure 5, and the only difference consists in the use of a T-bar 327 to form the sealing member with the free edge of the door. Said T-bar 327 has the web 328 thereof riveted to the lower vertical 45 flange of the slope sheet 320. One relatively narrow flange 329 of the T-bar extends inwardly over the flat portion 51 of the door. The other flange 331 is extended first horizontally outwardly and thence inclined downwardly and outwardly, so as to 50 co-operate with the correspondingly formed edge of the door C.

55 From the preceding description, considered in connection with the drawings, it will be observed that there is a common characteristic in the sealing floor plates 27; 229—230; and 329—331, illustrated in Figures 1, 5 and 6, respectively. This common characteristic is the formation in the floor sealing plates of 60 a groove-like recess facing downwardly or toward the corresponding adjacent edges of the doors, the said corresponding edges of the doors having complementally formed edges whereby to obtain the sealing effect.

55 While I have herein shown and described

what I consider the preferred manner of carrying out my invention, the same is merely illustrative and I contemplate all changes and modifications which come within the scope of the claims appended hereto.

70

I claim:

1. In a car, the combination with the body having a door opening therein, said opening being defined by fixed metal body members, said members on some sides of the opening being of arcuate cross section; and a pivoted sheet metal door, some margins of said door having correspondingly formed integral arcuate ribs to thereby form sealed joints, said door having an upwardly offset portion 80 within the central zone thereof.

2. In a car, the combination with a car body having a door opening with floor plates therearound, certain of said floor plates being of arcuate cross section; and a pivoted sheet metal floor door, said door having integrally formed ribs on its margin, said ribs being of corresponding arcuate formation and co-operable with said floor plates, said door having the central zone thereof upwardly 90 offset from the general plane of the edge portions.

3. As an article of manufacture, a sheet metal door, said door having integrally formed, diagonally arranged, relatively narrow ribs incorporated therein, said ribs being of gradually decreasing height from approximately the center of the door toward the corners of the door and offset upwardly from the plane of the sheet.

4. As an article of manufacture, a sheet metal door, said door having integrally formed, diagonally arranged ribs incorporated therein, said ribs being of gradually decreasing height from approximately the center of the door toward the corners of the door, margins of said door having integrally formed shallow ribs of arcuate cross section adapted to cooperate with correspondingly formed members around the door opening.

5. In a drop-bottom car having a slope sheet along the side thereof, terminating at its lower edge in a vertical section, the combination with an edge strip having a flange secured to said vertical section and another seal-forming flange; of a pivotally mounted, sheet metal drop-bottom door having its free edge shaped to correspond with said seal-forming flange and co-operable with said seal-forming flange.

6. In a drop-bottom car having a slope sheet along the side thereof, terminating at its lower edge in a vertical section, the combination with an edge strip having a flange secured to said vertical section and another seal-forming flange; of a pivotally mounted drop-bottom door having its free edge conformed to and co-operable with said seal-forming flange of said strip, said door being comprised of sheet metal and having inte-

grally incorporated therein, intermediate the free and hinged edges of the door, an upwardly arched indentation.

7. In a drop bottom car having an under-frame, including cross members and provided also with side stakes and a side wall terminating above the level of the cross members; of a slope sheet secured along its upper edge to the lower edge of the side wall and having its lower edge supported on said cross members, said sheet having integrally formed strengthening corrugations therein.

8. In a car, the combination with a body having a door opening therein, said opening being defined by fixed body members, said members on some sides of the opening being of grooved formation with the open side of the grooved formation extending toward the corresponding edges of the door; and a pivoted metal door having corresponding margins thereof integrally and complementally formed to cooperate with said body members of grooved formation to thereby form sealed joints on said edges, said door having a raised central portion.

In witness that I claim the foregoing I have hereunto subscribed my name this 14th day of April, 1928.

ALLAN S. BARROWS.
